United States Patent Office.

EPHRAIM S. WILLIAMS, OF CAMBRIDGE, MASSACHUSETTS.

Letters Patent No. 95,297, dated September 28, 1869.

IMPROVED CHUCK.

The Schedule referred to in these Letters Patent and making part of the same.

To all whom it may concern:

Be it known that I, EPHRAIM S. WILLIAMS, of Cambridge, in the county of Middlesex, and State of Massachusetts, have invented certain new and useful Improvements in Mandrels, Chucks, &c.; and I do hereby declare that the following is a full and exact description thereof, reference being had to the accompanying drawings, and to the letters of reference marked thereon.

The nature of my invention consists in providing the threaded part of a chuck or mandrel with one or more open slots running transversely across the threads, the object of said slot being to render the same self-cleaning.

To enable others skilled in the art to make and use my invention, I will proceed to describe its construction and use.

Drawings.

Figure 1 is a perspective view, showing the mandrel.

Figure 2 is a perspective view, showing a chuck.

I construct my improved mandrels, chucks, face-plates, &c., in the ordinary manner, except in the chuck-screw C of the mandrel A, fig. 1, I form a groove, e f, and in the female screw of the face-plate or chuck, H, I form a slot, l m. These slots, e f and l m, may extend through all of the threads, as shown, or only through one or two of them, the design of the slots being to clear the thread of any chips, dust, or dirt that may be in them.

The advantages and operation of this device are too obvious to need explanation.

What I claim as my invention, and desire to secure by Letters Patent of the United States, is—

The chuck-screw, when provided with a slot, e f or l m, substantially as described and for the purpose set forth.

EPHRAIM S. WILLIAMS.
